J. BRANDSTETTER

PHONOGRAPH STOP

Filed March 17, 1924

Inventor:
Josef Brandstetter
by Albert Scheibl Attorney

UNITED STATES PATENT OFFICE.

JOSEF BRANDSTETTER, OF CHICAGO, ILLINOIS.

PHONOGRAPH STOP.

Application filed March 17, 1924. Serial No. 699,814.

To all whom it may concern:

Be it known that I, JOSEF BRANDSTETTER, citizen of the United States, residing at Chicago, in the county of Cook and State of Illinois, have invented certain new and useful Improvements in a Phonograph Stop; and I do hereby declare the following to be a full, clear, and exact description of the invention, such as will enable others skilled in the art to which it appertains to make and use the same.

My invention relates to the class of phonograph stops in which a brake member is automatically released when the tone arm of the phonograph reaches a point corresponding to that at which the needle of the reproducer is close to the end of the groove in the record. For this purpose, the presented invention aims to provide a stop which can readily be assembled in its entirety, which can easily be attached to a standard type of phonograph, which can readily be adjusted with a high degree of accuracy as to its stopping point, which will maintain the accuracy when in service, and which will be both durable and inexpensive.

In my copending application No. 671,266, filed Oct. 27, 1923, I have disclosed a stop for this purpose, which stop was designed for applying the brake to the inner face of the depending rim of the turntable of a phonograph. Being thus arranged, the stop of my said copending application can be employed only on phonographs in which sufficient head room is available under the turntable and hence is not adapted for use with a good many makes of the phonographs now on the market. Furthermore, this type required the turntable to be detached from the phonograph to afford access for fastening the stop in its proper position, thereby making it difficult to judge the proper operative position during such attaching. It also required two separate springs for urging the brake member and the latching member in different directions and required a bendable member for affording the adjustment needed to insure the desired sensitivity of the stop.

My present invention provides a phonograph stop somewhat allied in principle to the aforesaid but adapted to be attached to the phonograph while the turntable is in its normal position, thereby enabling even an inexperienced person to fasten it in its prop-

er position. Moreover, my present invention provides a stop construction in which a single spring serves the double function of urging both the brake member and the latching member in certain directions, and one in which a simple screw or bolt affords the needed adjustment for sensitiveness. Still further and also more detailed objects of my present invention will appear from the following specification and from the accompanying drawings, in which—

Fig. 1 is a perspective view of a phonograph stop embodying my invention, with the tone arm of the phonograph partially shown in dotted lines as about ready to trip the latching member so as to release the brake.

Fig. 2 is a plan view of the same embodiment, with full lines showing the brake member in its latched or inoperative position, and with dotted lines indicating the operative or braking position of this member.

Fig. 3 is an elevation of the same embodiment, taken from the bottom of Fig. 2.

Fig. 4 is a fragmentary vertical section taken along the line 4—4 of Fig. 2 and showing the position of the latching member with respect to the top ledge of the supporting member and the brake lever while the latching member is holding the brake lever in its retracted or inoperative position.

Fig. 5 is a similar view, showing the position of the brake lever and the latching lever after the latter has been tripped so as to set the brake.

Fig. 6 is a horizontal section taken from the line 6—6 of Fig. 3 and looking upward.

Fig. 7 is a perspective view of the metal portion of the brake member.

In the embodiment of the drawings, the stop of my invention includes a supporting member having a base plate 1 provided with a plurality of screw holes 2, these screw holes being desirably of a considerable number and distributed over the base plate so that screws may be inserted through any two of them, according to the positions which may be most advantageous on the particular phonograph to which the stop is to be attached. This base plate is desirably part of a metal punching having an integral riser 3 and having a horizontal ledge 4 extending from the top of this riser and overhanging a portion of the base 1.

Pivoted to the riser 3 on a horizontal rivet 5 is a latching member which is here shown in the form of a bell-crank lever having an upwardly directed operating arm 6 and also 5 having a latching arm 7 which extends under the top ledge 4 of the supporting member. The arm 6 of this latching lever has a trip arm 8 pivoted to its free end through a friction joint 9, which friction joint offers 10 sufficient resistance so that the trip arm 8 and the said latching lever will normally move as a unit although they can be moved with respect to each other whenever the latching lever 7 is positively stopped against 15 movement in either direction.

Extending vertically through the top ledge 4 is a pivot pin 9 which affords a pivotal mounting for the brake member of my stop. This brake member also is shown in 20 the form of a bell-crank lever having a handle arm 10 disposed for extending substantially concentric with the turntable of the phonograph on which the stop is employed, and having a brake arm 11 provided with a 25 couple of depending jaws 12 which jaws are bent towards each other during the manufacture of the stop so as to grip a brake block 13 of felt between them.

The portion of the braking arm adjacent 30 to its pivotal mounting rests substantially flatwise on the top ledge 4 of the supporting member and when the latching lever is in its latching or brake-retracting position, one edge of the braking lever engages a vertical shoulder on the arm 7 of the latching lever, as shown in Figs. 1 to 3 inclusive. This shoulder is here shown as forming a vertical edge of an upwardly projecting finger 14 on the said arm 7, and the top of this finger is 35 desirably disposed at an acute angle to the said shoulder edge so as to be parallel to the top of the ledge 4 when the latching lever is moved to its releasing position of Fig. 5. The arm 7 of the latching lever also has a 40 portion disposed for limiting the movement of this arm in its unlatching direction, for which purpose I am here showing this arm as carrying a downwardly directed extension adapted to have its tip engage the base 45 plate 1 of the supporting member.

To return the latching lever to its latching position, I provide spring means associated with it, and for this purpose I desirably employ the same spring 16 which continuously urges the brake lever towards its brake-setting or operative position. In the 50 illustrated embodiment I am showing this spring as interposed between a finger 17 formed from the latching lever and a depending finger 18 formed from the brake member.

With the stop thus constructed and fastened to a suitable portion of the phonograph in proper relation to the turntable 19 55 which supports the record 20, the tone arm

21 of the phonograph is first moved to the position in which the needle carried by its reproducer is adjacent to the end of the record, after which the trip arm 8 is moved into contact with the tone arm, this being 70 done while the brake is in its operative position with the latching lever disposed as shown in Fig. 5. Then the tone arm is returned manually to its starting position, the brake is released by moving the handled 75 lever 10 in a direction which is clockwise in Figs. 1 and 2, and the rotation of the turntable is started in the usual manner. This leaves the latching lever in the position of Fig. 4, until the tone arm acts upon this 80 lever through the trip arm 8, thereby moving the lever about its pivot 5 (in a direction which is clockwise in Fig. 4) so as to release it from engagement with the adjacent 85 arm 22 of the brake member.

While the brake lever is retracted, the latching lever engages the bottom of the ledge 4, thus holding the top of the shoulder-carrying projection 14 at a predetermined height above this ledge. Consequently, the releasing of the brake will always be accomplished by a predetermined extent of movement of the latching lever, provided that the main arm 22 of the brake member is 90 always at the same height above the ledge 4. However, since the spring 16 always tends to raise the latching arm 7 and since this arm has its projection 14 engaging the bottom of the brake arm 22 while these parts 95 are in the position of Fig. 5 during the initial adjusting of the stop, the spring may cause the finger 14 to lift the brake arm 22 off the ledge 4, so that the accuracy of the adjustment will depend on the extent of this 100 lifting. In practice, a slight lifting of the brake arm during the adjusting may be permitted, so as to avoid undue friction of the brake arm in moving over the ledge 4, hence I provide means for limiting the extent of 105 this lifting. For this purpose I desirably provide a threaded member, such as a screw 23 extending through a slot 24 in the brake arm 22 and having its head overhanging the top of this brake arm. By adjusting this 110 screw, I can readily vary the extent of the 115 said permitted lifting, thereby varying the 120 said adjustment, while the shank of this 125 same screw may engage one end of the slot 24 to limit the movement of the braking member in its brake-releasing direction, I 130 preferably provide an auxiliary stop member 25 depending from the brake arm and adapted to engage one edge of the ledge 4.

It will be obvious from the above that my entire stop is quite simple, inexpensive of manufacture, easily installed and easily adjustable. Furthermore, since the spring 16 has a large portion of its length disposed 135 below the ledge 4, this ledge serves as a

guard for preventing the fingers of the user from touching the spring while he is reaching down and moving the handle 10 during the starting of the phonograph. Hence no particular care is required on the part of the user when manipulating my stop.

However, while I have illustrated and described my stop in a highly desirable embodiment, I do not wish to be limited to the details of the construction and arrangement thus disclosed, it being obvious that many modifications might be made without departing either from the spirit of my invention or from the appended claims.

15 I claim as my invention:—

1. A phonograph stop comprising a supporting member having a riser portion and an elevated ledge connected to the riser portion; a brake lever pivoted to the said ledge on a vertical axis; a latching lever pivoted to the riser on a horizontal axis and having a shoulder adapted to engage the brake member for holding the latter in its inoperative position; and spring means continuously tending to move the latching lever into its said holding position and to move the brake lever into operative position.

2. A phonograph stop as per claim 1 in which the said ledge and the brake member have interengaging parts arranged for limiting the movement of the brake member out of its operative position.

3. A phonograph stop as per claim 1, in which the brake member is provided with a downwardly directed finger disposed for engaging an edge of the said ledge to limit the movement of the brake member away from its operative position.

4. A phonograph stop as per claim 1, in which the said ledge overhangs the spring so as to serve as a guard for the spring.

5. A phonograph stop as per claim 1, in which the latching member includes a lever extending in a generally horizontal direction and projecting below the said ledge and having a downwardly directed stop finger, the said lever also having an upwardly directed portion affording the said shoulder for engaging the brake member, and the supporting member having a base portion adapted to be engaged by the said stop finger to limit the movement of the latching lever in its unlatching direction.

55 6. A phonograph stop comprising a supporting member having a base portion, a riser portion extending upwardly therefrom and an elevated ledge overhanging the base

portion; a brake lever pivoted to the said ledge on a vertical axis, a latching lever pivoted to the riser portion on a horizontal axis and having a shoulder adapted to engage the brake lever to hold the latter in its inoperative position, and a single spring connecting the two levers for continuously urging the latching lever into a position in which its shoulder effects the said holding and continuously urging the brake lever towards its operative position.

7. A phonograph stop as per claim 1, in which the latching lever and the brake lever are each provided with a finger and in which the spring means comprise a tension spring connecting the said two fingers.

8. A phonograph stop as per claim 1, in which the latching lever and the brake lever are each provided with a finger and in which the said spring means comprise a tension spring connecting the said two fingers, the finger on the brake lever being directed towards the said base portion and the spring extending below the said ledge so as to be guarded by the latter.

9. A phonograph stop as per claim 1, in which the latching lever has portions respectively adapted to engage the bottom of the said ledge and the top of the said base portion for limiting the movement of the latching lever in respectively opposite directions about its said pivotal mounting.

10. A phonograph stop as per claim 1, in which the latching lever has a portion disposed for engaging the bottom of the ledge to limit the movement of the lever in its latching direction when the lever is in its latching disposition and has another portion engaging the brake lever to limit the movement of the lever in the same direction when the brake is unlatched.

11. A phonograph stop as per claim 1, in which the latching lever has a portion disposed for engaging the bottom of the ledge to limit the movement of the lever in its latching direction when the lever is in its latching disposition and has another portion engaging the brake lever to limit the movement of the lever in the same direction when the brake is unlatched, and adjustable means carried by the support for limiting the movement of the brake lever by its last named engagement with a portion of the latching lever.

Signed at Chicago, Illinois, March 11th, 1924.

JOSEF BRANDSTETTER.
